UNITED STATES PATENT OFFICE

2,276,069

PILE RESISTOR

Walter H. Smith, Wilkinsburg, Pa., assignor to
 Westinghouse Electric & Manufacturing Com-
 pany, East Pittsburgh, Pa., a corporation of
 Pennsylvania

Application September 7, 1940, Serial No. 355,788

4 Claims. (Cl. 201—51)

This invention relates to resistors of the carbon pile type.

Pile resistors are well known and have been utilized in regulating apparatus and systems for a number of years. The known pile resistors, however, were formed of a plurality of discs of resistance material, such as carbon or the like, supported by insulated rods which touched the edge of the discs of high resistance material or that were supported by threading the disc on a central insulating rod or tube. In the known structures, the supporting members for the discs were employed merely to support the discs so that when pressure which is applied to the assembly during use was released, the discs did not separate uniformly throughout the length of the assembly. Under these conditions, it was found that the voltage drop is not uniformly distributed throughout the assembly nor is heat developed evenly therein, but instead a larger voltage drop is encountered at the end of the assembly where pressure is applied and released.

In a copending application of C. C. Whitaker, Serial No. 355,802, filed September 7, 1940, there is disclosed and claimed a pile resistor in which the discs of resistance material are supported on an insulating member to which a positive force is applied when pressure is released for effecting a positive movement of the insulating member through the stacked discs for obtaining an even separation of the discs when pressure is released. The pile resistor of C. C. Whitaker is effective for accomplishing the desired object of effecting an even separation of the discs when the resistor is employed as a regulator for load regulation. However, it has been found that where such a resistor is employed as a part of a voltage regulating apparatus, that it is not sensitive enough for obtaining the desired voltage regulation, since a change in the voltage which it is desired to regulate of only a few volts, will not provide the force necessary for effecting the desired even separation of the discs.

It is an object of this invention to provide a pile resistor, the discs of which are disposed to be evenly positioned when pressure is applied or released to provide a uniform resistance throughout the unit, and give a resistor which is sensitive to small differentials in voltage when the resistor is employed as a part of a voltage regulator.

Another object of this invention is to provide a pile resistor in which the discs of the pile are carried by an insulating member which is supported in a substantially frictionless manner, and

a positive means separate from the pressure applying means and the stack of discs for effecting a positive movement of the insulating member throughout the stack to secure an even separation of the discs when pressure is released.

Other objects of this invention will become apparent from the following description when taken in conjunction with the accompanying drawing, in which:

10 Figure 1 is an elevational view, partly in section, of a resistor embodying the teachings of this invention;

Fig. 2 is an elevational view, partly in section, of an embodiment of this invention;

15 Fig. 3 is an elevational view, partly in section, of a resistor illustrating another embodiment of this invention.

Fig. 4 is a fragmentary view, partly in section, of the resistor of Fig. 2 modified in accordance with the teachings of this invention;

20 Fig. 5 is a fragmentary view, partly in section, of the resistor of Fig. 3 modified in the same manner as the resistor of Fig. 4; and

Fig. 6 is a diagrammatic view of a circuit in which the resistor of Fig. 1 is utilized.

25 Referring to Fig. 1, this invention is illustrated by reference to a resistor element 10 formed of a plurality of discs 12 of resistance material, such as carbon or the like. Any predetermined number of discs 12 may be utilized, depending upon the resistance value which it is desired to secure in the assembly. In the particular embodiment illustrated, the discs 12 are of the circular type having a predetermined thickness and having openings centrally positioned therein so that when the discs are stacked, as illustrated, the openings are aligned.

30 In order to support the discs 12 in their aligned relation, an insulating supporting member is so disposed as to extend through the aligned openings of the discs. This insulating supporting member comprises a metallic rod 14 having metal sleeves 16 disposed thereon and attached thereto as by means of the pins 18 and a tube of insulating material 20 which extends between the sleeves 16. The discs 12 are in direct contact with the tube 20 of insulating material, such as porcelain, Micalex, Pyrex glass, or the like, the weight of the discs at least causing contact between the discs and the tubular member 20 along the upper edge of the tube 20. In all cases, the insulating tubular member 20 extends beyond the ends of the stacked and aligned discs 12.

35 In order to retain the discs 12 in assembled position on the tube 20 of insulating material, a

fixed stop or end plate 22 is disposed at one end of the stacked discs 12 and is secured in any well known manner to a panel (not shown). The fixed stop 22 has an opening 24 therein of a size suitable for permitting movement of the insulating tube 20 therethrough, as will be explained more fully hereinafter. Adjacent the other end of the stacked discs 12, a pressure plate or disc 26 is positioned to bear against the face of the end of the discs 12, the pressure plate being provided with a projecting end cap 28 which has a recess therein for receiving one of the sleeves 16 and the end of the tubular member 20. The end cap 28 is also provided with an opening through which the metallic rod 14 extends in a direction away from the pressure plate 26 and the stacked aligned discs. The pin 18, which is utilized for holding the sleeve 16 in position with respect to the metal rod 14, may also be utilized for securing the end cap 28 in position with respect to the end of the insulating member 20 and stacked discs 12.

As illustrated, the fixed plate 22 supports the one end of the insulating member 20, the opening 24 in the fixed plate 22 being of sufficient size to permit longitudinal movement of the insulating member therethrough when pressure is applied or released. In order to support the other end of the metallic rod 14 which carries the insulating member 20, a bracket or flange plate 30 is provided on the panel (not shown) the plate having an opening 32 therein through which the end of the metallic rod 14 projects. As illustrated, the opening 32 is also of sufficient size to permit longitudinal movement of the metallic rod 14 therethrough when pressure is applied or released. A spring member 34 is provided about the end of the metallic rod 14 and is held in position with respect to the rod and biased against the plate 30 by means of a cap 36 which engages the end of the spring 34. The cap 36 may be threaded onto the end of the rod 14 and is disposed to be adjusted for varying the tension of the spring 34, the purpose of which will be explained more fully hereinafter.

In order to apply pressure to the assembled discs, any suitable means can be employed such as the bell crank lever 38 formed by the short arm 40 and the long arm 42. The bell crank lever is disposed for movement about a pivot 44 in response to either the bias of a spring 46 which is secured between a fixed point 48 on the panel (not shown) and a projecting lug 50 of the bell crank 38 or in response to a force applied to the end of the long arm 42, as will be hereinafter described. The end of the short arm 40 which is disposed to bear against the end of the end cap 28 may be of any desired form so long as it does not interfere with the movement of the metallic rod 14. Thus, the end of the short arm 40 may be either a fork or may merely have an enlarged opening therein through which the rod 14 is disposed for unrestricted movement.

With the metallic rod 14 and the tubular member 20 carried thereby secured to the end cap 28 of the pressure disc 26, when pressure is applied to the end cap 28 as by means of the spring 46, the discs are compressed, being forced to the right, as illustrated, against the fixed stop or end plate 22, and simultaneously with the compression of the discs 12, the tubular member 20 of insulating material is moved longitudinally through the central openings of the discs relative to the discs. As will be apparent, since the tubular member 20 is free to move through the fixed

stop or end plate 22 and the plate 30, and since the fixed stop 22 limits the movement of the discs 12, a large movement between the discs 12 and the tubular member 20 will be obtained adjacent the fixed stop 22, the relative movement between the discs 12 and the tubular member 20 progressively increasing from the end of the stack adjacent the pressure disc 26 until it reaches a maximum adjacent the fixed stop 22. At the same time, the movement of the insulating member 20 and metallic rod 14 towards the fixed plate 22 effects a compression of the spring 34 so that it will be biased to effect a movement of the metallic rod 14 away from the fixed stop 22 when the pressure is released.

With the discs under pressure, as described hereinbefore, when the pressure is removed from the end cap 28, it is found that the spring member 34 effects a positive movement of the rod 14 and insulating member 20 away from the fixed stop 22 throughout the stacked discs 12, and that the frictional resistance between the discs 12 and the tubular member 20 cooperates with the positive movement of the insulating member 20 to effect a movement of the discs 12 adjacent the fixed stop 22 at the same time that the discs adjacent the pressure disc 26 move as a result of the release of the compressive force on the assembled disc. The amount of the positive movement of the insulating member 20 through the stack of discs 12 will depend upon the amount of pressure released, since, in all cases, the spring 34 is adjusted in a predetermined manner to so cooperate with the pressure applying means that, as the pressure is released, the spring will insure a movement of the rod 14 away from the fixed stop 22 in an amount just equal to the movement towards the fixed stop when an equal amount of pressure is applied.

In addition to effecting a movement of the discs 12, it is found that the positive movement of the tubular member 20 relative to the discs when the pressure is released, effectively breaks up any static friction between the discs and the tubular member.

As will be understood, the frictional resistance between the discs and the tubular member 20 of insulating material will be a maximum adjacent the fixed stop 22, and will be progressively decreased in the direction of the pressure disc 26, since the relative movement of the tubular member 20 with respect to the discs 12 when pressure is released progressively decreases from the fixed stop 22 in the direction of and to the pressure disc 26.

In the embodiment illustrated in Fig. 1, the weight of the assembly is carried by the plates 22 and 30. In some cases, it is found that the friction encountered in carrying the stacked assembly in the plates 22 and 30 is detrimental where it is desired to provide a very sensitive and uniform operation of the resistor. In order to provide a resistor which is sensitive and responsive to very small changes in voltage, it is desired to support the insulating member 20 which carries the assembled discs in a substantially frictionless manner with respect to the plates 22 and 30 so that the insulating member 20 is relatively free moving with respect to the supporting plates when pressure is applied or released.

In the embodiment illustrated in Fig. 2, the metal rod 14 and the insulating member 20 project through enlarged openings 24 and 32 in the plates 22 and 30, respectively, in a frictionless manner, the plates 22 and 30 being employed for

the purpose of guiding the rod 14 when it is moved. In this embodiment the plate 22 carries a bracket 52, the bracket 52 being secured thereto in any suitable manner. At the end of the bracket 52 one end of a leaf spring member 54 is secured as by means of the screws 56, the leaf spring 54 being disposed to extend downwardly in the path of movement of the rod 14. As illustrated, the rod 14 has its end machined to provide a shoulder, the small end of the rod 14 projecting through a suitable opening in the end of the leaf spring 54 and being carried thereby. As will be understood other means such as cotter pins extending through the rod 14 may be employed in place of the machined shoulder. The leaf spring 54 may be of any desired strength, depending upon the amount of force which is to be applied to the assembly.

At the other end of the stacked discs, the plate 30 carries a flange 58, at the end of which is pivotally hung a link 60 which is provided with an opening 62 through which the rod 14 projects, the rod seating on the lower surface of the opening and being supported by the link. As illustrated in Fig. 2, the force may be applied to the link 60, as by means of the bell crank 38 in a manner similar to that illustrated in Fig. 1. Since the link 60 is pivotally carried by the flange 58, it is apparent that this support is substantially frictionless with respect to the plate 30.

With the metallic rod 14 carried by the link 60 and the leaf spring 54, the rod 14 and insulating member 20 are relatively free moving with respect to the plates 22 and 30. Further, since the leaf spring 54 opposes the application of force to the insulating member, it is quite apparent that any force which has been applied is released, a positive movement of the rod 14 and insulating member 20 in a direction away from the fixed stop 22 is secured in a substantially frictionless manner with respect to the plates 22 and 30 throughout the stack of discs 12 to effect a substantially even separation of the discs. The positive movement insured by the use of the leaf spring 54 is sufficient to effect a movement of the insulating rod 20 throughout the stack in a direction away from the fixed stop 22 in an amount equal to the movement of the insulating rod in a direction toward the fixed stop 22 when an equal amount of pressure is applied.

Referring to Fig. 3 of the drawing, another embodiment of this invention is illustrated. In this embodiment, the metallic rod 14 and insulating member 20 carrying the assembly of the discs 12 are supported in a substantially frictionless manner with respect to the plates 22 and 30 by means of two leaf springs 54 and 64, respectively. As illustrated, the support for carrying the leaf spring 54 is the same as outlined in the embodiment of the invention illustrated in Fig. 2. The support for leaf spring 64 is similar to the support for leaf spring 54, being formed by a bracket 66 secured to the plate 30, one end of the leaf spring 64 being, in turn, secured to the bracket 66, while the other end is provided with a small opening through which the metallic rod 14 projects. As illustrated, the projecting end of the metallic rod 14 to the left of the leaf spring 64 is provided with a shoulder for abutting the leaf spring 64, so that as the metallic rod 14 is moved in a direction towards the fixed stop 22, both of the leaf springs 54 and 64 are forced to the right and tend to bias the metallic rod 14 and insulating tubular mem-

ber 20 carried thereby in a direction away from the fixed stop 22.

In the embodiment illustrated in Fig. 3, the leaf springs 54 and 64 support the metallic rod 14 and assembly carried thereby in a substantially frictionless manner with respect to the plates 22 and 30, and also provide a positive force for effecting a positive movement of the insulating member 20 throughout the stack of discs when pressure is released.

As illustrated in each of Figs. 4 and 5, the coil spring 34 of Fig. 1 may be utilized with the structures of Figs. 2 and 3. The use of the coil spring and the adjustable nut 36 with the particular structures of Figs. 2 and 3 is of advantage where the spring members 54 and 64 are not very strong but are used primarily for supporting the metallic rod 14 and the assembly carried thereby in a substantially frictionless manner with respect to the plates 22 and 30. Further, the tension of spring 34 can readily be adjusted so that when embodied in either of the structures illustrated in Figs. 2 and 3, a finer degree of adjustment can be obtained and the apparatus of Figs. 2 and 3 can be more widely employed in industry where the pressures encountered will vary to a considerable extent. In all of the structures of Figs. 2 through 5, the metallic rod 14 and the assembly carried thereby are supported in a substantially frictionless manner with respect to the plates 22 and 30, and a positive drive, which is separate from the pressure applying means and from the stacked discs, is provided for insuring a positive movement of the insulating member throughout the discs for obtaining an even separation of the discs when pressure is released.

Referring to Fig. 6, the resistor 10 of Fig. 1 is illustrated as employed in a voltage regulating system for regulating the voltage generated from a generator 68. The armature 70 of the generator is illustrated as being connected by conductors 72 and 74 to a load 76. A switch 78 is provided in the load circuit for closing the circuit through the load 76. A shunt field winding 80 of the generator 68 is illustrated as connected in shunt circuit relation with the armature 70 between the conductors 72 and 74. The resistor element 10 of this invention is connected in series with the shunt field winding 80 between the conductors 72 and 74. Since it is desired to control the voltage generated by the generator 68, an electromagnetic coil 82 is also disposed to be connected between the conductors 72 and 74 so that the voltage across the winding 82 is indicative of the voltage across the load 76.

As illustrated, the bell crank 38 employed as the pressure applying means for the pile resistor 10 is mechanically connected at the end of its long arm to an arm 84, one end of which carries an iron or magnetic portion 86 disposed to be actuated by the energization of the coil 82. When energized, the coil 82 tends to lift the iron or magnetic core portion 86, thereby rotating the bell crank 38 in a counterclockwise direction against the bias of the spring 46 to decrease the pressure applied to the stacked discs, thereby increasing the resistance in circuit with the field winding 80.

In operation with the switch 78 closed and the tension of the springs 34 and 36 adjusted in a predetermined manner, so that with normal or a predetermined voltage across conductors 72 and 74, a predetermined pressure is applied to the resistor element 10 for maintaining a prede-

terminated amount of resistance in the shunt field circuit. If for any reason the voltage generated by the armature 10 fluctuates from this predetermined normal value of generated voltage, as, for example, if the voltage generated increases above the predetermined value, the coil 32 will become sufficiently energized to overcome the pull of the spring 46 to cause the bell crank 33 to rotate in a counterclockwise direction about its pivot to release some of the pressure from the stacked discs 12. As the bell crank 33 rotates to release the pressure on the stacked discs, the spring member 34 functions to effect a positive movement of the insulating member throughout the discs in a direction away from the fixed stop 22. The frictional resistance between the discs of the assembly and the tubular insulating member, as the tubular insulating member is moved through the stack away from the stop 22, effects an even separation of the discs, giving a substantially uniform voltage drop across the stacked discs. The amount of the movement of the insulating member, as effected by the action of the spring 34 when the pressure is released, is equal to the movement of the insulating member in the opposite direction when an equal amount of pressure is applied to the stacked assembly. This increase in the resistance introduced in circuit with the field winding 20 reduces the excitation of the coil 32 so that the resulting generated voltage is decreased.

If, however, the voltage generated is decreased from the normal generator voltage value, the pull of the spring 46 effects a movement of the bell crank 33 in a clockwise direction about its pivot, whereby more pressure is applied to the carbon disc assembly, thereby decreasing the resistance in circuit with the shunt field winding 20 to increase the generator voltage.

Where the resistor element of this invention is employed, either for the purpose of load regulation for voltage regulation as described, a very close control is obtained. This is especially true where the resistor element is utilized in voltage regulating systems where regulation must be provided for maintaining very small differentials of voltage of the order of less than two volts, it being found that in a system as illustrated in Fig. 6 that the element is sufficiently sensitive to maintain the voltage generated substantially constant with a permissible variation of only two volts. This close control is obtained only where a positive drive for the insulating member carrying the discs 12 is provided which is separate from the pressure applying means. The frictionless supporting of the metallic rod and insulating member, as described hereinbefore, cooperates with the positive drive for providing an extremely sensitive regulating apparatus.

By employing the resistor element of this invention, it is found that the desired results can also be obtained with a small disc assembly, since fewer discs of the high resistance material are necessary for obtaining the desired voltage drop in the element where the positive drive is employed, the construction described effectively breaking up the static friction in a uniform manner between all of the discs in the assembly and providing for a uniform heating of the assembled discs in service.

Although this invention has been described with reference to a particular embodiment thereof, it is, of course, understood that the invention is described as illustrative only and is not to be interpreted in a limiting sense.

I claim as my invention:

1. A pile resistor comprising, a plurality of discs of resistance material having central openings therein, an insulating member extending through the central openings to support the discs in stacked alignment, a stop disposed at one end of the aligned discs, means for applying pressure disposed at the other end of the aligned discs for applying pressure to the discs and moving the insulating member longitudinally through the stack, and a spring means separate from the pressure applying means disposed for effecting a positive movement of the insulating support member in a direction away from the stop, the frictional resistance between the discs and the insulating member as the insulating member moves therethrough effecting an even separation of the discs throughout the stack when pressure is released.
2. A pile resistor comprising, a plurality of discs of resistance material having central openings therein, an insulating member extending through the central openings to support the discs in stacked alignment, a stop disposed at one end of the aligned discs, means for applying pressure disposed at the other end of the aligned discs for applying pressure to the discs and moving the insulating member longitudinally through the stack, and a support member disposed adjacent each end of the aligned discs for carrying the insulating member in a substantially frictionless and relatively free moving manner with respect to the stop, one of the support members comprising a leaf spring member disposed for effecting a positive movement of the insulating member in a direction away from the stop when the pressure is released, the frictional resistance between the discs and the insulating member cooperating with the positive movement of the insulating member to effect an even separation of the discs throughout the stack when pressure is released.
3. A pile resistor comprising, a plurality of discs of resistance material having central openings therein, an insulating member extending through the central openings to support the discs in stacked alignment, a stop disposed at one end of the aligned discs, means for applying pressure disposed at the other end of the aligned discs for applying pressure to the discs and moving the insulating member longitudinally through the stack, means for supporting and carrying the insulating member in a substantially frictionless manner for rendering it relatively free moving with respect to the stop when pressure is applied and released, and a spring means separate from the pressure applying means disposed for effecting a positive movement of the insulating member in a direction away from the stop whereby the frictional resistance between the discs and the insulating member as the insulating member moves therethrough effects an even separation of the discs throughout the stack when pressure is released.
4. A pile resistor comprising, a plurality of discs of resistance material having central openings therein, an insulating member extending through the central openings to support the discs in stacked alignment, brackets disposed at opposite ends of the stack and having openings therein for receiving the ends of the insulating member to guide it when moved, a stop associated with one of the brackets for limiting the movement of the stack in a direction towards the stop, a leaf spring member associated with each of the

brackets and engaging the insulating member for supporting it in a substantially frictionless manner with respect to the guide brackets, and means for applying pressure disposed at the end of the stacked discs opposite the stop for applying pressure to the discs and moving the insulating member longitudinally through the stack and guide brackets, the leaf springs effecting a positive

movement of the insulating support member in a direction away from the stop when the pressure is released, the frictional resistance between the discs and the insulating member cooperating with the positive movement of the insulating member to effect an even separation of the discs throughout the stack when pressure is released.

WALTER H. SMITH.
